SYNCHRONIZING SYSTEM

Frank R. Brick, Elizabeth, N. J.

Application February 20, 1943, Serial No. 476,567

17 Claims. (Cl. 178—69.5)

My invention relates in general to the field of facsimile transmission and reception and more particularly concerns a novel method for maintaining facsimile apparatus at remotely disposed stations in synchronism.

In facsimile systems, a scanning member at the transmitter traverses an image and generates electrical currents fluctuating in accordance with the lights and shades of elemental areas thereof. These currents are then transmitted by wire or radiation to a distant receiver where these currents are amplified and applied to a scanning member operable under the surface of a recording sheet.

It is essential that the scanning members at the transmitter and the receiver be operated at identical speeds and corresponding phase positions. Heretofore, a start stop synchronizing method was employed in which the transmitting scanner was operated at a substantially predetermined speed while the receiving scanner was operated at a somewhat higher speed.

Periodically, at the termination of each scanning cycle apparatus would be halted and would then be released upon the receipt of a synchronizing signal generated at the transmitter.

The transmitter synchronizing signal normally would be a pulse of relatively short duration which when received, would energize solenoidal means to release the scanning halting mechanism. The disadvantages of the start-stop synchronizing system are well known in the facsimile art. It is recognized that this system has been the prime cause of wear in facsimile equipment. This wear would be the result of the periodic halting and thus jarring of the relatively large masses which necessarily had to be stopped.

The start-stop system was also a severe limitation to high speed facsimile operation. Thus a receiver when operated in a start-stop manner, at relatively high speeds, would soon develop mechanical faults which required constant servicing. Furthermore, the start-stop system depended upon the fact that during the movement of the scanning members, these members were actually out of synchronism with respect to each other.

In order to eliminate the deleterious effects of continuous stopping and starting of the recording equipment, I propose to utilize a continuous synchronizing system wherein both transmitter and recorder scanning members operate continuously at identically the same speed and in the same phase throughout the recording process.

It will be evident that facsimile transmitters

and recorders which may be operated from the same alternating current power line may be operated in synchronism with each other without the use of special synchronizing equipment. This, of course, may be accomplished by employing similar synchronous driving motors at both the transmitter and recorder which, when energized by currents from a single alternating current power line, would operate at equal speeds.

10 However, facsimile transmissions are not often between points which have available a common alternating current power transmission system. In fact, in mobile equipment such as facsimile devices adapted for aerial installations, the power supplies are usually of the direct current type and thus there is no common power supply which may be relied upon to effect a coordination of the movements of the transmitter and receiver scanning members.

20 More specifically, my invention contemplates the operation of a facsimile recorder from a direct current power supply at a synchronous speed which is determined by the speed of the facsimile transmitting scanner. I may operate 25 my facsimile transmitting scanner from any available power supply. Should the power supply be of the alternating current type, then I utilize a synchronous motor at the transmitter to drive the scanning members at a corresponding speed. 30 The picture currents generated by the scanning member are applied to an amplifier and are then caused to modulate a radio frequency carrier for transmission purposes.

In addition to the picture current modulation, 35 I may continuously modulate the radio frequency carrier with a synchronizing current which is a function of the frequency of the current driving the transmitting synchronous motor. This synchronizing current is continuous and may comprise a modulation at the power system frequency.

The picture currents may themselves be a modulated audio frequency carrier in order to preclude interference between the relatively low frequency synchronizing current and the picture currents. The transmitted wave which therefore comprises a radio frequency carrier modulated by a picture current of audio frequency and by a synchronizing current of power frequency is then intercepted and detected at the receiver.

50 Here the picture and synchronizing currents are separated and selectively applied to a recording mechanism and to a synchronizing mechanism respectively. The recording scanning mechanism is driven by a synchronous motor energized from a local source of electrical energy which may

be in the form of a direct current battery or power line.

In order to translate the electrical energy of the direct current supply to alternating currents of synchronous frequency, I utilize a thyratron inverting circuit which operates to convert energy delivered by the battery into an alternating current suitable for driving the scanning means. The frequency of the alternating current delivered by a thyratron inverter is exactly that of an impressed synchronizing frequency which in this example is the transmitted power frequency synchronizing current.

Thus it will be evident that the synchronous receiving motor drives the recording mechanism at synchronous speed while deriving its energy from a direct current power supply. Accordingly the need for a start-stop mechanism has been eliminated entirely.

In another modification of my continuous synchronizing system, I may employ a conventional type of transmitter which may be operated by a synchronous or non-synchronous motor and/or upon alternating or direct current. A governor may be employed upon the transmitter motor to cause the operation thereof of a substantially predetermined rate. This motor drives the transmitting scanning members which in turn generate picture currents. At the termination of each transmitting scanning cycle, a synchronizing signal for a particular frequency or amplitude characteristic is generated and transmitted.

At a remotely disposed receiver, the picture and synchronizing signals are detected and are applied to the recording and synchronizing mechanism respectively. The synchronizing pulses if of a distinctive amplitude are separated from the received signal and are impressed upon a thyratron inverter which operates to translate direct current into alternating current at the frequency of the incoming synchronizing signals.

This alternating current which is therefore of a frequency that is a function of the speed of the transmitting scanner is applied to a synchronous motor which drives the recording scanner. Again, it will be evident that the recording scanner may be caused to operate at a speed identical to that at the transmitter. However, it is necessary in facsimile transmission to ensure that the transmitting and recording scanning members operate at the same speed and in the exact phase.

It is obvious that if the recording mechanism is operating at the same rate as the transmitting mechanism, the phasing operation need occur only once during the transmission, or subsequent to any momentary interruption which may cause a relative phase displacement. To this end, I incorporate a start-stop mechanism into the recorder which mechanism is substantially similar to that which heretofore has been employed to maintain synchronism.

In this system, a lever or similar member is in the path of a projection upon the scanning members. The incoming synchronizing signals are impressed upon electromagnetic means which remove the lever from the path of the drum projection, when energized. Consequently, this facsimile recorder will operate in the following manner:

At the beginning of a transmission, should the transmitter and receiver drums be out of phase, the projection on the drum will engage the synchronizing lever and preclude further rotation thereof. The driving motor is permitted to rotate

by a friction clutch which is interposed between the drum and the motor.

Upon the receipt of a synchronizing signal, the halting lever will disengage the drum and permit the continued rotation thereof. However, as previously mentioned, since the driving motor is operating at a speed which is determined by the frequency of the synchronizing pulses, the projection on the drum will arrive at the synchronizing lever just as the synchronizing signal causes the removal thereof. Thus, although the synchronizing lever will operate in response to received synchronizing signals, there will normally be no start-stop action and the friction clutch engaging the motor and the drum will not operate.

It is only at the beginning of a transmission that the synchronizing lever operates to adjust the phase position of the scanning member. Also, if during the transmission, an interruption should occur which might cause a phase displacement, the synchronizing lever will immediately operate the start-stop mechanism to re-phase the scanning members.

It is therefore an object of my invention to provide a facsimile transmitter and recorder which continuously operates in synchronism with each other.

Another object of my invention is to provide for a picture transmission system wherein a continuous synchronizing current generated at the transmitter is transmitted with the picture signals.

Still another object of my invention is to provide for a picture transmission system wherein a thyratron inverter is utilized at the recorder to translate direct current available into alternating current at a frequency which is a function of the speed of the transmitting scanner.

A further object of my invention is to provide for a picture transmission system wherein a series of transmitting synchronizing impulses operate to control a thyratron inverter circuit operable to drive a recording motor.

It is a further object of my invention to provide a facsimile recording system driven by a synchronous motor energized through a direct current source.

Still another object of my invention is to provide a facsimile recording system which continuously operates at the speed and in the same phase as the transmitter.

Still a further object of my invention is to provide a novel combination of a continuous synchronizing system and a start-stop synchronizing system whereby accurate control over the speed and phase of the recording scanning members is obtained.

These and other objects of my invention will now become apparent from the following description taken in connection with the drawings, in which:

Figure 1 is a schematic illustration of a transmitter adapted to transmit a combined picture signal and continuous synchronizing current.

Figure 2 is another embodiment of a facsimile transmitter operable to generate and transmit combined picture signals and synchronizing impulses.

Figure 3 is a schematic diagram of a facsimile recorder adapted for continuous synchronization with a corresponding transmitter.

Figure 4 is a diagrammatic representation of a facsimile recorder adapted for continuous syn-

chronization and incorporating a start-stop mechanism for proper phasing thereof.

A facsimile transmitter for combining a picture current and a continuously synchronizing current is diagrammatically illustrated in Figure 1 and reference is now made thereto. A transmitting drum 11 is rotatably supported and continuously driven by motor 12 through any suitable positive coupling 13. The type of motor utilized to drive the drum 11 will be described in a later paragraph.

An optical scanning system 14 is mounted upon a feed screw mechanism and in the well known manner is caused to be displaced axially with respect to the drum 11. Thus the light spot 15 traverses a continuous helical path about the surface of the drum.

Light reflected from the drum impinges upon the cathode 16 of a photoelectric cell 17 which is fixed relative to the optical system 14 and thus is displaced accordingly. The photoelectric cell 17 energized by battery 21 thus carries a current which varies in accordance with the lights and shades of the elemental areas of the picture traversed by the light spot 15. This current in passing through resistor 22 develops a corresponding voltage thereacross which is impressed upon an amplifier 23.

The frequencies of the picture currents generated may vary between 0 and a maximum which is normally an audio frequency. These currents are then caused to modulate a relatively low frequency wave in a modulator 24. Thus, the output of an audio frequency oscillator 25 is impressed upon a modulator 24 tube with the amplified picture currents to produce a picture modulated audio frequency.

This current may be amplified to any desired level and transmitted to the remote station. Any transmission means may of course be employed, namely, a telephone communication line or a radio frequency transmitter. As illustrated, the picture currents are impressed upon a circuit 26 wherein they modulate a radio frequency carrier which is then radiated by means of antenna 27.

Returning now to the source of motive power 12 which causes rotation of the drum and axial displacement of the optical scanning system, the motor 12 is preferably a synchronous motor energized from an alternating current supply. If an alternating current supply is unavailable, then a vibrator and storage battery may be utilized in combination to generate an alternating current of approximately the desired frequency or a self-excited thyratron inverter may be employed in connection with a direct current power line to generate alternating currents of the desired frequency.

In any event, the speed of the drum 11 and the scanner 14 is a function of the frequency of the impressed alternating current. To obtain a synchronizing current which is a function of the speed of operation of the combination of drum and optical scanning member, I therefore connect the radio frequency carrier modulating circuit directly to the alternating current power supply to the motor. Thus the transmission line 31 causes the modulation of the radio frequency carrier by an alternating current of a frequency equal to that driving the motor 12. Accordingly, the energy radiated from the antenna 27 comprises a radio frequency carrier modulated in accordance with the lights and shades of the picture supported upon drum 11

and in accordance with a continuously applied alternating current of the driving motor frequency.

If space radiation is employed for transmission as illustrated, then the synchronizing current may be of the same frequency as the motor supply current. However, if a telephone transmission line is employed for interconnection with a distant receiver, I have found that such lines do not permit the unimpeded transmission of low power frequencies of the order of sixty cycles per second.

Thus to transmit a synchronizing current over a telephone line, I may utilize a harmonic of the power current. Thus if the fifth harmonic or 300 cycles per second is employed, there will still be no interference with the picture currents.

The transmitted wave is intercepted at a receiving circuit which may be of the form indicated in Figure 3. Thus, the schematically illustrated radio frequency circuits 41 and the associated antenna 42 are utilized to receive and demodulate the transmitted radio frequency energy. This energy is, as illustrated, applied to two parallel channels which function to separate the components of the transmitted signal. Thus a parallel combination of high pass filter 43 and low pass filter 44 are utilized to selectively transmit the received picture currents and the received synchronizing current respectively.

As schematically indicated in Figure 3, the high pass filter comprises a combination of series capacitance 45 and shunt inductance 46. Conversely, the low pass filter for discriminating against the impressed picture currents while permitting the unimpeded passage of the synchronizing currents is represented as series inductance 47 and shunt capacitance 48.

The picture currents flowing out of high pass filter 43 are impressed upon a suitable cascade of amplifiers 52 to raise the signal to the recording level. Following this, the signal is impressed upon a full wave rectifier 53 to obtain a unidirectional signal which in turn is impressed between a recording stylus 54 and a conductive rotatable drum 55.

As schematically illustrated in Figure 3, the drum 55 is driven by positive coupling to a synchronous motor 56 through a gear reduction box 57. The gear box 57 also functions to cause suitable rotation of shaft 61 which through the agency of worm 62 and worm gear 63 causes the rotation of feed screw 64 as is well known in the art.

Rotation of the feed screw 64 causes axial displacements of a scanning mechanism 65 which is maintained in engagement with the feed screw through a nut which engages therewith. The axially movable scanning member 65 supports the conductive stylus 54 in engagement with a sheet of sensitized recording paper mounted upon the conductive drum 55.

Thus it may be seen that rotation of motor 56 will cause corresponding rotation of the drum 55 while scanning stylus 54 is displaced axially. The point of the stylus therefore follows a helical path which is similar to that of the scanning light beam at the transmitter as will hereinafter be explained.

The rectified currents may be impressed upon the rotatable conductor drum 55 in any suitable manner as by a brush and slip-ring and the like.

The type of recording paper employed will determine the level of amplification required for the incoming picture signal and a saturable device

may be placed in circuit with the stylus to preclude the combustion of the recording sheet. It will be understood that this invention is not limited to the conductive stylus and platen arrangement illustrated, but may be employed with any type of transmitting and receiving scanning systems.

Thus the amplified picture currents obtained from the rectifier 53 could be impressed upon a lamp to vary the intensity thereof and to record upon a photographic or similarly sensitized film. The motor 56, as hereinabove mentioned, is of the synchronous type which as is well known will operate at a speed determined solely by the frequency of the applied alternating currents.

To obtain a driving current for motor 56 of frequency equal to that employed for driving the transmitter motor 12 of Figure 1, I employ a thyratron inverting circuit for translating direct current available into this alternating current. The thyratron may be one of several well known forms.

As illustrated in Figure 3, a parallel type inverter comprising two thyratron tubes 71 and 72 is employed. The direct current available for energizing motor 56 is illustrated by battery 73, the negative end of which is joined to the cathodes of the thyratron tubes 71 and 72 and the positive end of which is joined to the center tap 74 of the primary of transformer 75 through reactor 76. The extremities of the primary winding 75 are joined to the anodes of the thyratron tubes, and a condenser 77 is shunted across the anodes. The grids of the thyratron tubes are energized from alternate ends of the secondary 81 of the transformer 82 which in turn is energized from the output of the low pass filter 44.

If needed, suitable amplifying equipment may be placed in circuit with the output of the filter 44 to raise the level of the synchronizing current. The thyratron grids are normally biased negatively by the battery 83. In operation, the thyratron circuit illustrated translates the power delivered by battery 73 into alternating current which is caused to flow in the transformer secondary 84 and which thus energizes the synchronous motor 56.

As is well known, in a gas filled triode or thyratron such as 71 or 72, the grid exercises control over the operation of the tube only when there is no current flow therein. As soon as conduction is established between anode and cathode, the grid loses control of the space current and does not regain control until conduction ceases.

In the circuit illustrated, the grids of the tubes are alternately driven positive and negative. When one grid is driven more positive by the synchronizing current induced within the transformer secondary 81, its tube conducts and the battery 73 delivers the required current. This current flows through the reactor 76 and through the secondary 75 of the output transformer and thus a current is induced in the transformer secondary.

The condenser 77 acts as a commutating device to extinguish the tube after conduction begins since normally the tube would continue to conduct independently of the variations in the grid voltage. When the grid of the other thyratron is driven more positive, its tube discharges and a surge of current flows from battery 73 through the reactor 76 and through the transformer secondary 75. As will be noted, this current is in the direction opposite to the current which flows when the first tube conducts and thus an alter-

nating current is induced in the secondary 84 and is in turn impressed upon the synchronous motor 86.

Further it is to be noted that the alternating current developed is of frequency identical with the synchronizing current induced within the transformer 81. Therefore, the synchronous motor 56 will rotate at a speed which corresponds to the speed of rotation of the drum 11 at the transmitter. The thyratron inverter will translate the direct current available into alternating current of the required frequency and thus continuous synchronization and continuous operation of the recording drum 55 is obtained.

Thus the transmitter and a remotely disposed receiver will operate in exact continuous synchronism even though the power supply utilized for driving the synchronous motors is not derived from the same alternating current transmission line.

A further modification of the continuous synchronizing system illustrated in Figures 1 and 3 is illustrated in the transmitter and receiver combination of Figures 2 and 4. In Figure 2, the transmitter is similar to that which has been conventionally used for the generation of facsimile signals. Thus the motor 101 which is preferably of the non-synchronous type is driven from a power supply which may be either direct or alternating current. This motor is governed to a substantially constant speed by a centrifugal device which operates to open the main circuit when the speed exceeds a predetermined value.

The motor 101 through gear reduction drive 102 positively and continuously drives transmitting drum 103. To this drum is secured the image to be transmitted by any suitable means.

An optical system 104 and associated photoelectrical cell 105 is caused to move axially with respect to the drum by means of a feed screw driven from the motor 101 in the manner similar to that schematically shown in Figure 3. Thus a light spot 106 traces a helical path about the drum.

The variations in light which fall upon the photoelectric cell are translated into corresponding fluctuating electric currents which are then amplified by the amplifier 107 and fed to the audio frequency modulator 111 with an audio frequency oscillation generated in oscillator 112.

Thus the output of the modulator 111 is an audio frequency current amplitude modulated in accordance with the lights and shades of picture areas. This current is then amplified by amplifier 113 to a suitable level for driving the radio frequency modulating and transmission circuits 114. The output currents are then radiated by antenna 115.

Periodically at the termination of each revolution of the drum 103, a synchronizing signal is generated and impressed upon the transmission means. This synchronizing signal may be generated in a manner more completely described in my copending application Serial No. 361,480, filed October 17, 1940. The synchronizing signal is generated by utilizing a characteristic indication 116 such as a black stripe across the drum surface. During the period in which this black strip passes under the light beam of the optical scanning system, the switch 117 is closed by means of cam 121 coupled to the drum by shaft 122.

Closure of switch 117 as described in the aforementioned copending application raises the amplification level of the circuit 113 and thus the passage of the characteristic indication 116 under

the light beam 105 will cause an increase in the amplitude of the generated signal. The frequency of the synchronizing pulses generated in this manner will correspond exactly with the angular speed of the drum 103. Therefore, the signal radiated from the antenna 115 will comprise a radio frequency carrier modulated by a picture current for the major portion of each cycle, and modulated by an increased amplitude synchronizing pulse at the termination of each scanning cycle.

As will become evident from a description of the receiver indicated in Figure 4, various other forms of synchronizing signals may be employed in connection with this type of system. Referring now to the receiver of Figure 4, an antenna 140 is employed to intercept the signals radiated by antenna 115 illustrated in Figure 2. The voltages developed therein are demodulated in the radio frequency circuits 141 and impressed upon an amplifier 142. The output of the amplifier 142 will comprise the combination of synchronizing impulses and picture currents.

As illustrated, one circuit from the output of amplifier 142 is fed to a full wave rectifier 143, the output of which is impressed between the conductive rotatable drum 144 and a conductive recording stylus 145. Attached to the drum 144 by means of shaft 146 is a cam 147 having a projection 151 which operates once during each drum revolution to interrupt the circuit through cam switch 152. Interruption of this circuit, as will be obvious, precludes current flow between the conductive stylus 145 and the drum 144. As will hereinafter be explained, the projection 151 is arranged with respect to the drum and with respect to the incoming signals so that the currents are interrupted cyclically during the reception of the synchronizing signal.

This of course prohibits the recording of the high level synchronizing pulse which may affect the recording sheet.

Another parallel circuit from the output of amplifier 142 is joined to a synchronizing pulse amplifier and discriminating circuit 153. This circuit 153 normally may comprise a vacuum tube amplifier biased below cut off so as to preclude normal current flow unless the signal rises above a predetermined maximum. Since the synchronizing impulses are of particularly high level, such a circuit is biased to preclude the flow of normal picture currents and thus the output of the synchronizing pulse amplifiers 153 is merely a succession of synchronizing signals.

It is to be remembered, that any form of synchronizing signal may be employed. Thus if synchronizing signals of a distinctive frequency characteristic were transmitted, a selective filter would be used at the receiver to separate these from the picture currents and transmit them through the synchronizing pulse channel indicated.

The synchronizing pulses appearing in the output of amplifier 153 are used to synchronize a thyratron inverter operating to translate a direct current power supply 154 at the receiver into alternating currents of a frequency suitable for driving the synchronous motor 155. If the frequency of the incoming synchronizing pulses is relatively low as compared with the frequency of the desired alternating current, a frequency multiplier 156 may be utilized to raise the frequency to that desired.

Obviously it would be easy to raise the frequency since the succession of synchronizing

75 pulses are rich in harmonics and thus a high harmonic thereof may be employed. These pulses are impressed between the grid and cathode of a thyratron tube 157, the grid of which is biased to a suitable value by means of battery 161. The inverter illustrated is known as a relaxation type in that a single gas filled triode is employed.

As illustrated, the positive terminal of the main direct current supply 154 is joined at the anode of the thyratron 157 through inductance 162 and the primary 163 of an output transformer 164. A series circuit of a condenser 165 and inductance 166 shunts the anode to the cathode of the gas filled tube. When the grid of the thyratron 157 is driven more positive with respect to the cathode by an incoming synchronizing pulse or by the positive cycle of a higher harmonic thereof, the tube will conduct and a surge of current will flow in the primary 163 of transformer 164 and so induce a corresponding current in the secondary 167.

The circuit of condenser 165 and 166 acts as a commutator and causes the extinction of the thyratron 157 subsequent to the discharge thereof. The cycle will be repeated for each cycle during which the grid of the tube 157 is driven in the positive direction. Thus the output current will comprise an alternating current of a frequency which is a function of the incoming synchronizing signals which is in turn a function of the speed of operation of the transmitting scanning mechanism and accordingly the synchronous motor 155 will be maintained in continuous operation and continuous synchronism with respect to the corresponding drum 103 at the transmitter.

As described above, it is not only necessary that the recording drum be in rotational synchronism with the transmitting drum but in exact phase synchronism therewith. The reason for this becomes apparent if it is recognized that an overlapping exists at the transmitting image and at the recording sheet which is mounted upon the drum 144.

45 Thus it is extremely important that the stylus 145 begin to record the picture immediately following the overlap period on the recording drum 144 and terminate the recording of this picture just prior to the passage of the paper overlap under the recording stylus. At the transmitter illustrated in Figure 2 it may be seen that the position of the characteristic indication 116 and the position of the projection on the cam 121 determine the position of the synchronizing impulse with respect to the overlap of the image to be transmitted. In fact, as indicated in the co-pending application above mentioned, the image mounting means is colored black in order that the synchronizing pulse be generated exactly during the overlap period. Consequently, to ensure proper phasing at the receiving circuit even though I employ a continuously synchronized drum as regards speed of rotation, I utilize a novel combination of continuous synchronizing and a start-stop mechanism.

As illustrated schematically in Figure 4, the synchronous motor 155 drives the drum 144 through a friction clutch 171 which comprises a driving plate 172 coupled directly to the motor shaft 173, a driven plate 174, coupled directly to the drum 144 through shaft 175 and an interposed layer of leather or similar frictional backing 176.

A spring may be used to maintain frictional

engagement between the three elements 172, 174 and 176 of the clutch. A synchronizing lever 177 pivotally mounted by a chain 181 is normally biased by means of tension spring 182 so that the edge 177' is in the path of a projection 174' on the driven plate 174. Accordingly, during the revolution of the drum 144, the projection 174' will engage the lever 177 to permit slipping within the clutch and to halt the rotation of drum 144.

However, as indicated in Figure 4, the output of the synchronizing pulse amplifier also energizes a synchronizing electromagnet 183. This magnet when energized will attract the magnetic member 184 and cause the rotation of synchronizing lever 177 about the pivot 181. This will remove the end 177' from the path of the projection 174' to permit unimpeded rotation of the drum.

If at the beginning of a transmission, the overlap of the drum 144 is out of phase with respect to the overlap of the drum 143, the synchronizing lever 177 will preclude rotation of the drum 144 until a synchronizing signal is received to energize magnet 183. At this point the drum 144 will be released to rotate under the driving influence of motor 155.

However, as previously mentioned, the driving motor is operated through thyratron inverter 157 which is in turn energized by a synchronous alternating current. Thus rotation of drum 144 will occur at exactly the same speed as the transmitting drum 103. Therefore, the projection 174' on the driven plate 174 will arrive at the edge 177' of the synchronizing lever just as the synchronizing signal arrives and draws the lever out of the path of the driven plate.

Due to this action, the friction clutch will not operate during the normal picture recording cycle but will only operate if the recording drum 144 falls out of phase with respect to the transmitting drum 103. This condition may prevail at the beginning of a picture transmission where it is difficult to ascertain the exact position of the recording drum; also if any line or transmission faults occur which tend to interrupt the signal and thus tend to slow down motor 155.

Under these circumstances, the friction clutch will operate to maintain proper phasing of the transmitting drum. Although it is possible to operate the drum in a start-stop phase, this will rarely occur since it is seldom that line faults will cause misphasing thereof. Therefore, the above described modification of facsimile transmitter and recorder taken in connection with Figures 2 and 4 provides a system in which continuous synchronization is obtained by the use of a thyratron tube which translates direct current into alternating current power for consumption by a synchronous motor, at the synchronous desired frequency.

Furthermore, this system compensates for any misphasing condition which may arise at the beginning of a transmission or in the course of a transmission. It will be evident that any form of synchronizing signal may be utilized for the type of circuit indicated in Figure 4.

If the constant frequency continuous type of synchronizing signal is employed, then it will be necessary to combine this with the transmission of impulses at the end of each scanning line for the operation of the synchronizing magnet. By an amplitude discriminating means, these amplitude synchronizing pulses may be separated

from the continuous synchronizing signal and be applied to the electromagnet 183.

Thus it is evident that a combination of the transmitters illustrated in Figures 1 and 2 and the recorders illustrated in Figures 3 and 4 is possible and that any form of synchronizing signal may be employed. Either system eliminates the constant wear which has normally been experienced by prior start stop systems. The drums are continuously rotated and if they are stopped at all, it is for rephasing, which is a necessary feature.

It should be noted that the thyratron circuits employed are driven from a direct current source which is capable of delivering enough power to drive facsimile signalling motors. Normally the power rating of this type motor is of the order of thirty to sixty watts and as is well known, such power is easily handled by gas filled triodes or thyratrons.

Since the specific disclosure hereinabove set forth relating to continuous synchronizing systems and combined start-stop and continuous synchronizing systems may be subject to continuous modification by those skilled in the art and still fall within the spirit and scope of my invention, I prefer to be bound only by the scope of the appended claims.

I claim:

1. In a signalling system, a transmitter and a receiver, movable members at said receiver and said transmitter, means for motivating said movable members at said transmitter, and means for transmitting a signal which is a function of the speed of said transmitter movable members, a direct current source of power at said receiver, means for receiving said transmitted signals and means including an electronic circuit, said received signal and said source of power for motivating said receiver movable members at the speed of said transmitter movable members, said electronic circuit comprising a gaseous discharge tube inverter for translating said direct current power into alternating current.

2. In a signalling system, a transmitter and a receiver, movable members at said receiver and said transmitter, means for motivating said movable members at said transmitter, and means for transmitting a signal which is a function of the speed of said transmitter movable members, a direct current source of power at said receiver, means for receiving said transmitted signals and means including an electronic circuit, said received signal and said source of power for motivating said receiver movable members at the speed of said transmitter movable members, said electronic circuit comprising a gaseous discharge tube inverter for translating said direct current power into alternating current, said inverter operating in accordance with said received signal.

3. In a picture transmission system, a transmitter and a receiver, a scanning member at said transmitter for translating the lights and shades of an image into correspondingly fluctuating image currents, means for motivating said scanning members, and means for generating a synchronizing current having a frequency which is a function of the speed of said scanning members, means for transmitting said image currents and said synchronizing currents, a source of power at said receiver, means for receiving said transmitted currents, a scanning member at said receiver for converting said received image currents into an image, means for motivating said

receiver scanning member including said power source, said received synchronizing currents and an electronic circuit.

4. In a picture transmission system, a transmitter and a receiver, a scanning member at said transmitter for translating the lights and shades of an image into correspondingly fluctuating image currents, means for continuously motivating said scanning members, and means for generating a synchronizing current having a frequency which is a function of the speed of said scanning members, means for transmitting said image currents and said synchronizing currents, a direct current source of power at said receiver, means for receiving said transmitted currents, a scanning member at said receiver for converting said received image currents into an image, means for motivating said receiver scanning member including said power source, said received synchronizing currents and an electronic circuit operable to translate said direct current power into alternating current power at a frequency which is a function of the frequency of said synchronizing.

5. In a picture transmission system, a transmitter and a receiver, a scanning member at said transmitter for translating the lights and shades of an image into correspondingly fluctuating image currents, means for continuously motivating said scanning members, and means for generating a synchronizing current having a frequency which is a function of the speed of said scanning members, means for transmitting said image currents and said synchronizing currents, a source of power at said receiver, means for receiving said transmitted currents, a scanning member at said receiver for converting said received image currents into an image, means for motivating said receiver scanning member at the speed of said transmitting scanning member, including a synchronous motor, said power source, said received synchronizing currents and an electronic circuit operable to translate said direct current power into alternating current power of a frequency which is a function of the frequency of said synchronizing current for energizing said synchronous motor.

6. In a picture transmission system, a transmitter and a receiver, a scanning member at said transmitter for translating the lights and shades of an image into correspondingly fluctuating image currents, a synchronous motor for continuously motivating said scanning member, a source of alternating current for energizing said synchronous motor, means for transmitting said image currents and an uninterrupted synchronizing current of frequency equal to said alternating current, means at said receiver for receiving said transmitted currents, a source of power at said receiver, scanning members at said receiver for recording said image currents, means for motivating said receiver scanning members at the speed of said transmitting scanning members including a synchronous motor, said receiver power source, said received synchronizing current and a thyratron tube having a central grid and anode, said thyratron being operative to translate the power of said receiver power source into alternating currents at said synchronizing current frequency for energizing said synchronous motor.

7. In a picture transmission system, a transmitter and a receiver, a scanning member at said transmitter for translating the lights and shades of an image into correspondingly fluctuating im-

age currents, a synchronous motor for continuously motivating said scanning member, a source of alternating current for energizing said synchronous motor, means for transmitting said image currents and an uninterrupted synchronizing current of frequency equal to said alternating current, means at said receiver for receiving said transmitted currents, a source of power at said receiver, scanning members at said receiver for recording said image currents, means for motivating said receiver scanning members at the speed of said transmitting scanning members including a synchronous motor, said receiver power source, said received synchronizing current and a thyratron tube having a control grid and anode, said thyratron being operative to translate the power of said receiver power source into alternating current, said received synchronizing current being selectively impressed upon said control grid for determining the frequency of said alternating current, said alternating current energizing said synchronous motor.

8. A picture receiver comprising means for receiving transmitted image currents and uninterrupted synchronizing currents, scanning members for recording said image currents, means for motivating said scanning members comprising a synchronous motor positively coupled to said scanning members, a direct current power source, a thyratron tube inverting circuit for translating said direct current into alternating current of a frequency which is a function of said received synchronizing current, and means for selectively impressing said synchronizing currents upon said thyratron circuit and said picture currents upon said scanning members.

9. A picture receiver comprising means for receiving transmitted image currents and uninterrupted synchronizing currents, a rotatable drum for carrying a recording sheet, and a recording scanner for traversing said sheet, a synchronous motor positively coupled to said drum and to said scanner, a direct current power source, means for translating said direct current power into alternating current power comprising a thyratron tube having a control grid, an anode and an anode circuit, said synchronous motor being coupled to said anode circuit, said direct current source being in said anode circuit, said synchronizing currents being impressed upon said grid.

10. A picture receiver comprising means for receiving transmitted image currents and uninterrupted synchronizing currents, a rotatable drum for carrying a recording sheet, and a recording scanner for traversing said sheet, a synchronous motor positively coupled to said drum and to said scanner, a direct current power source, means for translating said direct current power into alternating current power comprising a thyratron tube having a control grid, an anode and an anode circuit, said synchronous motor being coupled to said anode circuit, said direct current source being in said anode circuit, said synchronizing currents being selectively impressed upon said grid and said image currents being selectively impressed upon said scanner.

11. In a picture transmission system, a transmitter comprising a rotatable drum for supporting an image, a synchronous motor for driving said drum, an alternating current supply for energizing said synchronous motor, a scanning member cooperable with said drum for translating the lights and shades of said image into correspondingly varying image currents, means for generating a phasing signal at the termination

of each drum revolution and means for transmitting said image currents, said phasing signal and a current of the frequency of said alternating current.

12. In a picture transmission system, a transmitter comprising a rotatable drum for supporting an image, a synchronous motor for driving said drum, an alternating current supply for energizing said synchronous motor, a scanning member cooperable with said drum for translating the lights and shades of said image into correspondingly varying image currents, means for generating a phasing impulse of distinctive amplitude at the termination of each drum revolution, and means for transmitting said image currents, said phasing impulse and a current of the frequency of said alternating current.

13. In a signalling system; a first station having a movable member; a remotely disposed second station having a movable member; a source of driving power for said first station, and a source of driving power for said second station; means at said first station for generating picture signals to be transmitted; means at said second station for receiving said signals; a source of electrical energy at said second station for operating its associated source of driving power; means at said first station for generating synchronizing signals which are directly controlled by and are a function of the speed of operation of said first station movable member and means at said second station for producing from said source of electrical energy, signals of a frequency which is a function of said synchronizing signals for determining the speed of operation of said receiver.

14. In a picture transmission system; a first station having a movable member; a remotely disposed second station having a movable member; a source of driving power for said first station, and a source of driving power for said second station; means at said first station for generating picture signals in accordance with the lights and shades of a picture to be transmitted; means at said second station for receiving said picture signals and translating them back into lights and shades for recording; a source of electrical energy at said second station for operating its associated source of driving power; means at said first station for generating synchronizing signals which are directly controlled by and are a function of the speed of operation of said first station movable member, and a thyratron inverter at said second station for producing from said source of electrical energy, signals of a frequency which is a function of said synchronizing signals for determining the speed of operation of said receiver.

15. In a signalling system; a first station having a movable member; a remotely disposed second station having a movable member; a source of driving power for said first station, and a

source of driving power for said second station; means at said first station for generating picture signals to be transmitted; means at said second station for receiving said signals; a source of electrical energy at said second station for operating its associated source of driving power; means at said first station for generating synchronizing signals which are directly controlled by and are a function of the speed of operation of said first station movable member, and means at said second station for producing from said source of electrical energy, signals of a frequency which is a function of said synchronizing signals for determining the speed of operation of said receiver; means for periodically transmitting a phasing signal controlled by the position of said first station movable member, and means at said second station responsive to said phasing signal only when said movable member thereat is out of phase with said first station movable member for bringing them into phase.

16. In a signalling system; a first station having a movable member; a remotely disposed second station having a movable member; a source of driving power for said first station, and a source of driving power for said second station; means at said first station for generating picture signals to be transmitted; means at said second station for receiving said signals; a source of electrical energy at said second station for operating its associated source of driving power; means at said first station for generating synchronizing signals which are directly controlled by and are a function of the speed of operation of said first station movable member for transmitting a harmonic of said synchronizing signals; and means at said second station for producing from said source of electrical energy, signals of a frequency which is a function of said synchronizing signals for determining the speed of operation of said receiver.

17. In a signalling system; a first station having a movable member; a remotely disposed second station having a movable member; a source of driving power for said first station, and source of driving power for said second station; means at said first station for generating picture signals to be transmitted; means at said second station for receiving said signals; a source of electrical energy at said second station for operating its associated source of driving power; means at said first station for generating synchronizing signals which are directly controlled by and are a function of the speed of operation of said first station movable member; means at said second station for multiplying the frequency of said received synchronizing signals; and means at said second station for producing from said source of electrical energy, signals of a frequency which is a function of said synchronizing signals for determining the speed of operation of said receiver.
